UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 29, 1921. Serial No. 488,302.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening cases or hoods, and is of the same general type disclosed in my pending application, Serial No. 466,820, filed May 4, 1921 (now Patent No. 1,519,645, of December 16, 1924).

The casing comprises a body part and a cover or ceiling hinged to said body part. The body part is provided with a large front opening, through which the machine may be inserted into the casing, the banks of type-keys projecting forwardly from said casing after the machine has been inserted. A plate closes the front opening. An edge of the cover forms with an edge of the body part a slot at the front, through which the various carriage-operating handles, such as the line-space lever, the carriage-return finger-piece, and the carriage-release lever, extend. Sound-deadening means in the form of co-operating strips or cushions on the body part and cover are provided for closing the slot. The casing is provided with lateral extensions at the sides, over which the typewriter-carriage operates to the right and left, said casing thus completely enclosing the noise-producing parts of the machine.

The sound-deadening casing or hood of this invention is so designed that it may be used in connection with a long-carriage machine. For this purpose, the lateral extensions project a considerable distance from the sides of the casing so as to allow for the travel of the long carriage within the casing. It is desirable to have the lateral extensions detachably mounted on the casing, so that extensions of different lengths, to accommodate various lengths of carriages, may be used in connection with a main or central portion of the casing.

Another advantage of the detachable extensions is that they may be readily removed for clearance when the machine is mounted upon a swingable base of a drop-head desk, as the lateral extensions ordinarily project beyond the side edges of the swingable base.

For these purposes, the casing comprises a

central or main section, said section being substantially of the same width as the machine and having side openings to permit travel of the typewriter-carriage to the right and left. The main section being no wider than the machine, it is not necessary to remove it from the machine when the latter is lowered to the interior of the desk. When the machine is to be used, it is raised, together with the main casing applied thereto, and the lateral extensions are then mounted on the open sides of the main casing to close these openings to the exterior of the casing while permitting the typewriter-carriage to operate freely within the extensions. To enable the extensions to be readily attached to or detached from the main casing, there is provided simple fastening and holding means, which can be easily operated.

The lateral extensions are provided with slot-closing cushions which, when the lateral extensions are secured to the hood, form continuations of the slot-closing cushions of the central portion of the casing.

Other features and advantages will hereinafter appear.

In the accompanying drawings,

Figure 1 is a front view of the sound-deadening casing applied to an Underwood standard typewriting machine, said casing being partly sectioned.

Figure 2 is a plan view of the front portion of the casing, said front portion being disassembled.

Figure 3 is a side view, vertically sectioned, of the device shown in Figure 1.

Figure 4 is a view similar to Figure 3, but with the machine removed, showing the front cover-plate of the casing detached and the cover of the casing slightly raised.

In the drawings, there is shown an Underwood standard typewriting machine comprising a main frame 10 supported by feet 11 upon a base, and provided with a forward extension 12 in which are positioned banks of keys 13, said keys operating type-bars (not shown) to cause types carried by said type-bars to print against a platen 16, journaled in the end walls 17 of a platen-frame 18. Said platen-frame forms part of a carriage 20, mounted for letter-feeding movement upon a front rail 19 and a rear rail 21 on the main typewriter-frame. Said platen may be rotated in either direction by 110

finger-wheels 23, fixed upon shaft 24, upon which the platen 16 is mounted, said platen being rotatable also in line-spacing direction by a line-space handle 25 extending forwardly from said carriage. Said carriage is provided with other forwardly-extending operating handles, such as the carriage-return finger-piece 26 and carriage-release lever 27.

10 For deadening the sounds arising in the typing operations, there is provided a sound-deadening casing or hood, comprising a main or central section, indicated generally by the numeral 30 (Figure 1). Said main section comprises a body part 31 and a cover 32, hinged to said body part, said body part being provided with a rear wall 34, short side walls 35, and a front wall in the form of two end portions 36, there being a large space between said end portions to permit the insertion of the machine into the casing. When the machine has been positioned within the casing by means of abutments 38 on the rear wall 34, the forward extension 12 extends forwardly from the front of the casing to expose the banks of keys. To close all of the front opening not actually occupied by the forward extension 12, there is provided a front cover-plate 40, provided with turn-buttons 41 operating latches 42 which may be passed through openings 43 in the end portions 36, said openings 43 being similar in shape to latches 42 to permit the passage of said latches therethrough, said latches being turned after passing through said openings to catch behind the end portions 36 to lock the plate upon said front wall. To release the cover-plate, the latches must be turned until they occupy a position similar to openings 43, so that they may pass therethrough. After the plate has been applied, it will prevent spreading of the end portions since the distance between the latches is constant. The machine is thus enclosed at the front and rear, and partially at the sides by the short walls 35, and, to enclose the machine at the top, there is provided the cover 32, said cover 32 comprising a top wall or ceiling 45, said top wall extending forwardly and downwardly and terminating in a short front wall 44 some distance above the top of front cover-plate 40. To permit the machine, positioned in the interior of the casing, to be viewed, there is provided a transparent plate or window 46 in said ceiling 45. The front wall 44 terminating above the top of cover-plate 40 forms a slot at the front, through which the various carriage-operating levers extend, so that the ordinary typing operations may be carried on without raising the cover or removing the casing.

It will be observed that the main section 30 of the casing is open at the sides, with the exception of the small portion covered

by the short side walls 35. To close these passages to the exterior of the casing, and at the same time provide means which will permit the carriage to travel freely to the right and left, there are provided lateral extensions, indicated by the numerals 50 and 51, said extensions being closed at their outer ends by outer walls 52 and 53, their inner ends being open. Said inner ends are inserted in the side openings of the main section 30, said main section having outwardly-pressed overlapping side edges 54^a and 54 on the body part 31 and cover 32, respectively, to permit the extensions to fit into the main section. The overlapping side edges 54 do not extend around the front of the body part, that is, at the side edges of the end portions 36, said portions 36 being flat, and the front walls 60 of the extensions overlapping said end portions 36 at the front. The front cover-plate 40 is provided with outwardly-pressed, overlapping portions 62, to overlie the overlapping walls 60 of the lateral extensions, and thus assists in holding the extensions in position. To enable the carriage to operate freely in the lateral extensions, as well as in the main section 30, said extensions are each provided with a slot 65, which slots, when the extensions are mounted on the main section, form continuations of the front slot between the body part and cover of the main section, and in which the various carriage-operating levers may operate. To close all of the slots not actually occupied by the carriage-operating levers, there are provided, in the main section 30, co-operating cushions 66 and 67 and, in the extensions, co-operating cushions 68 and 69, forming, when the extensions are mounted on the main section, continuations of said cushions 66 and 77. The extensions are also provided with windows 71, similar to window 46, and forming continuations of the window 46, to permit the typewriter-carriage to be viewed when said carriage extends into said extensions.

To hold the extensions in position within the enlarged portions 54 at the sides of the main casing 30, there may be provided on said enlarged portions releasable locking members, such as spring-detents 80, having locking pins 81, which pass through openings in said enlarged portions 54 and said extensions, and similar locking members 85, mounted at the front on said extensions and passing through openings in said extensions and arms 86 of said end portions 36, said locking members being readily releasable against the action of their springs 83 to permit the extensions to be detached from the main casing 30. To render the locking members ineffective, the pins are withdrawn from the openings, and springs 83 are swung about their pivots 84 to swing the pins out of alignment with the respective openings.

Thus, if the typewriting machine is mounted upon the swingable base of a drop-head desk, and said base is but slightly wider than the typewriting machine, but not sufficiently wide to permit the entire casing to be lowered into the interior of the desk, the extensions 50 and 51 may be readily detached by merely releasing the locking members, leaving the main casing 30 in position as applied to the machine, said main casing being substantially the same width as the typewriting machine, so that it may be lowered therewith. When the machine is to be used, it need only be raised from the interior of the desk, and the lateral extensions 50 and 51 applied to the side openings of the main casing 30 by means of the locking members or spring-detents, and the machine will be completely enclosed and ready for use. Since the extensions may be of considerable size, it is desirable to provide them with supports or legs 90, pivotally mounted on the under surface of said extensions for movement to and from effective position.

25 With this arrangement it will be readily understood that the central section of the casing may be used with a typewriting machine having a short carriage or with a typewriting machine having a long carriage, and 30 that short or long lateral extensions 50, 51 may be attached to the central section according to the length of carriage in the machine.

Variations may be resorted to within the 35 scope of the invention, and portions of the improvements may be used without others.

Having thus described my invention, I claim:

1. A sound-deadening casing for a typewriting machine, comprising a central machine-containing section, overhanging extensions to accommodate the travel of the carriage, said extensions being substantially rigid and independent of the central section, and latching means for holding the extensions on the central section and releasable to permit bodily removal of the extensions from the central section.

2. A sound-deadening casing for a typewriting machine, convertible for use with carriages of different lengths and comprising a central machine-containing section having side openings to permit travel of the carriage, separate carriage-accommodating end sections constructed to fit over the side openings in the central section, and of length to correspond to the length of carriage to be used, and latching means to hold said end sections on said central section and releasable to permit bodily removal of the end sections from the central section and the substitution of end sections of different lengths, when required.

3. A sound-deadening casing for a typewriting machine having a carriage, com-

prising a central machine-containing section having side openings to accommodate the carriage when moved from its central position, hollow carriage-accommodating extensions to be placed over said openings when the machine is to be used and to be removed bodily, when the machine is not in use, to diminish the space occupied by the machine and casing, and latching means to hold said extensions in position when placed over the openings in the central section.

4. A sound-deadening casing, for a typewriting machine having a carriage, said casing comprising a main machine-containing section having open sides, carriage-accommodating extensions having open, inner ends fitting into the sides of the main section and having closed, outer ends to prevent escape of sound through the sides of the casing, the inner ends of the extensions and the side edges of the main section overlapping, and latching means passing through said overlapping portions to fasten the extensions on the main section and readily releasable to permit the bodily removal of said extensions from the main section.

5. A sound-deadening casing, for a typewriting machine having a carriage, comprising a main machine-containing section having open sides, carriage-accommodating extensions having open, inner ends fitting the sides of the main section at the opening and having closed, outer ends to prevent escape of sound through the sides of the casing, the inner ends of the extensions and the side edges of the main section overlapping, releasable means passing through said overlapping portions to fasten the extensions on the main section, and supports for the extensions attached thereto and serving to relieve the main section from strain when the extensions are attached thereto.

6. A sound-deadening casing for a typewriting machine, comprising a central machine-containing section having a body part and a cover part, and carriage-accommodating lateral extensions for the central section to close side openings between said body part and cover part when the cover is closed, and means for holding said extensions on said body part and releasable to permit the removal of said extensions when the machine is not in use.

7. A sound-deadening casing, for a typewriting machine having a carriage, comprising a central machine-containing section having side openings to accommodate the carriage when moved from its central position, and flanges around said openings and extending outwardly from shoulders formed at the inner edges thereof, hollow carriage-accommodating extensions to be placed over said openings when the machine is to be used and to be removed bodily when desired, the inner ends of said extensions fitting said

- flanges and engaging said flanges when the extensions are placed over said openings, and latching means to hold said extensions in position when placed over the openings 6 in the central section.
8. A sound-deadening casing for a type-writing machine, comprising a main machine-containing section having a body part and a cover part and being open at the sides, and hollow carriage-accommodating side sections of fixed length forming extensions of said body part and cover part and detachably mounted on the sides of said body part to permit complete removal therefrom 10 when desired.
9. A sound-deadening casing for a type-writing machine, said machine having a carriage and various carriage-operating levers extending forwardly therefrom, said casing 15 comprising a main section having a body part and a cover part, and extensions detachably mounted on said main section and in which said carriage operates, said body part and cover part forming a slot at the front in which said levers operate, said extensions having slots forming continuations 20 of the slot between said body part and cover part when said extensions are mounted on said main section.
10. A sound-deadening casing for a type-writing machine, comprising a central section, end sections detachable from the central section, and supports for said end sections connected therewith and spaced from 25 said central section.
11. A sound-deadening casing, for a type-writing machine having a carriage, comprising a central machine-containing section having side openings, end sections completely 30 detachable from the central section, means for releasably connecting said end sections with the central section, and supports pivotally mounted on said end sections at a substantial distance from said central section to be swung to and from effective 35 position to support said end sections.
12. A sound-deadening casing, for a type-writing machine having a carriage and an operating handle projecting therefrom, comprising 40 a central machine-containing section having a body part and a cover hinged to the body part at the rear and forming therewith, at the front, a slot to accommodate the travel of said handle, and, at the sides, openings 45 through which the carriage may pass, and lateral carriage-accommodating extensions releasably connected with said body part to close said openings when the cover is closed and having slots in prolongation of the first 50 slot.
13. A sound-deadening casing for a type-writing machine, said casing comprising a main section having a body part and a cover part, said body part having a front wall 55 provided with a large opening to permit the machine to be inserted into the casing, a cover plate mounted on the front wall of the body part, said main section being open at the sides, said machine having a carriage which operates beyond the sides of said 60 main section, and extensions mounted on said main section and in which said carriage operates, said extensions having open, inner ends fitting into the open sides of the main section and having closed, outer ends to prevent escape of sound through the sides of the casing, the inner ends of the extensions overlapping the front wall of the body part, said cover plate overlapping the inner ends 65 of the extensions, and releasable means passing through said overlapping portions to fasten the extensions upon the main section.
14. A sound-deadening casing for a type-writing machine, said casing comprising a main section having a body part and a cover part, said body part having a front wall provided with a large opening to permit the machine to be inserted into the casing, a cover plate mounted on the front wall of the body part, said main section being open at the sides, said machine having a carriage which operates beyond the sides of said 70 main section, extensions mounted on said main section and in which said carriage operates, said extensions having open, inner ends fitting into the open sides of the main section and having closed, outer ends to prevent escape of sound through the sides of the casing, the inner ends of the extensions overlapping the front wall of the body part, said cover plate overlapping the inner ends of the extensions. 75
15. A sound-deadening casing for a type-writing machine, said casing comprising a main section having a body part and a cover part, said body part having a front wall provided with a large opening to permit the machine to be inserted into the casing, a cover plate mounted on the front wall of the body part, said main section being open at the sides, said machine having a carriage which operates beyond the sides of said 80 main section, extensions mounted on said main section and in which said carriage operates, said extensions having open, inner ends fitting into the open sides of the main section and having closed, outer ends to prevent escape of sound through the sides of the casing, the inner ends of the extensions overlapping the front wall of the body part, said cover plate overlapping the inner ends of the extensions. 85
16. A sound-deadening casing for a type-writing machine, said machine having a carriage and an operating handle extending 90
- 100
- 110
- 120
- 125
- 130

therefrom, said casing comprising a central section, and extensions releasably mounted on said central section and in which said carriage operates, said central section having a slot therein through which the handle projects, one of said extensions having a slot forming a continuation of the slot in the central section.

17. A sound-deadening casing for a type-writing machine, said machine having a carriage and various operating handles extending therefrom, said casing comprising a central section, said central section having a slot therein through which the handles project, lateral extensions releasably mounted on the central section, said lateral extensions having slots therein forming continuations of the slot in the central section, slot-closing means extending along the slot in the central section, and slot-closing means extending along the slots in the lateral extensions.

18. A sound-deadening casing for a type-writing machine having a carriage, said casing comprising a central section, said central section comprising a body part and a cover forming the ceiling of said central section, two end sections, the end sections having ceilings independent of the ceiling of the cover, a window in the ceiling of the cover, and windows in the ceilings of the end sections, the windows in the end sections forming continuations of the window in the central section.

19. A sound-deadening casing for a type-writing machine having a carriage, said casing comprising a central section, said central section comprising a body part and a cover forming the ceiling of said central section, two end sections, the end sections having ceilings independent of the ceiling of the cover, a window in the ceiling of the cover, a window in the ceiling of each end section, the windows in the end sections forming continuations of the window in the central section, and means for releasably mounting said end sections on said central section.

20. A sound-deadening casing, for a type-writing machine having a carriage and an operating handle projecting therefrom, comprising a central machine-containing section having a body part and a cover hinged to the body part at the rear and forming therewith, at the front, a slot to accommodate the travel of said handle, and, at the sides, openings through which the carriage may pass, and lateral carriage-

accommodating extensions releasably connected with said body part to close said openings when the cover is closed and having slots in prolongation of the first slot; said extensions, when secured to the body part, extending beneath the side edges of said cover and serving to support the latter when in closed position.

21. A sound-deadening casing, for a type-writing machine having a carriage and an operating handle projecting therefrom, comprising a central machine-containing section having a body part and a cover hinged to the body part at the rear and forming therewith, at the front, a slot to accommodate the travel of said handle, and, at the sides, openings through which the carriage may pass, lateral overhanging carriage-accommodating extensions, of considerable length, releasably connected with said body part to close said openings when the cover is closed and having slots in prolongation of the first slot, and means for relieving said body part from supporting said extensions, said relieving means comprising, for each of said extensions, a support hinged thereto to be swung to ineffective position along said extension or to effective position.

22. A sound-deadening casing for a type-writing machine, comprising a central machine-containing section, overhanging lateral carriage-accommodating extensions, and legs hinged on the lower walls of said extensions for upward movement to ineffective positions along said lower walls or downward movement to effective positions, for supporting said extensions and thereby relieving said central section from strain.

23. A sound-deadening casing for type-writing machines, convertible for use with carriages of different lengths and comprising a main machine-containing section having a body-part and a cover-part, and being open at the sides, and hollow carriage-accommodating side sections forming extensions of said body-part, said side sections being of fixed lengths to correspond with any length of carriage selected, and detachably mounted on the sides of said body-part to permit bodily removal therefrom and substitution of side sections of other lengths when required.

JOHN WALDHEIM.
